UNITED STATES PATENT OFFICE.

JOHANNES KARL RUTHS, OF DJURSHOLM, SWEDEN, ASSIGNOR TO AKTIEBOLAGET VAPORACKUMULATOR, OF STOCKHOLM, SWEDEN, A CORPORATION.

STEAM-ACCUMULATOR PLANT AND METHOD OF OPERATING THE SAME.

Application filed June 20, 1919, Serial No. 305,622, and in Sweden June 29, 1918.

My invention relates to steam plants equipped with steam accumulators.

Steam accumulators, as previously known, are of two classes; first, those which even out the variations in exhaust of certain intermittently operating reciprocating steam engines, principally steam hammers, and, second, those which relieve boilers of variations in steam consumption or take care of variations between steam generation and steam consumption. An accumulator of the first class is chiefly an equalizer and has very little accumulating ability. It always discharges into a turbine operating at extremely low pressure, and has pressure variations of about six pounds and less, wherefore it cannot take care of any appreciable variations in consumption of the turbine. In the second class of accumulators large peaks of steam consumption are taken care of and large quantities of steam are accumulated. This causes large variations in pressure in the accumulator which give rise to many problems.

My invention relates to plants equipped with accumulators of the second class, wherein large variations of pressure occur. Previously to this invention it has been impossible to successfully build steam plants embodying this type of accumulator since no apparatus has been known which would confine the great pressure variations to the accumulator so that they would not affect other elements of the plant, particularly the boilers, which can not stand up under such heavy variations.

Consumers receiving steam from an accumulator have been relieved of variations in the accumulator by means of a reducing valve but this did not relieve those elements which are connected ahead of the accumulator of variations in pressure.

I have previously, in certain cases, designed plants with a nozzle of the Laval type inserted in the path of steam from the generator to the accumulator, serving an entirely different purpose from the arrangements of this invention. This device operated so that the generator pressure did not vary as did the pressure in the accumulator. How-

ever, this arrangement has many disadvantages and in many cases causes variations of pressure in the generator of greater magnitude than if the generator and accumulator were directly connected.

My present invention aims to provide an arrangement whereby the variations of pressure occurring in a plant embodying an accumulator of the second class as above described are confined to the accumulator so that the boilers are relieved of these pressure variations and can be operated at substantially constant pressure, while, at the same time, an independence between the momentary steam generation and steam consumption is effected and the accumulator will take care of all variations wherever they occur in the plant, thus, for the first time, making the use of such accumulators actually possible in practice in all manner of plants, no matter when or where the variations occur.

Other objects of my invention are to maintain a constant generator pressure automatically in a plant having a variation between steam generation and steam consumption; to relieve a plant of variations due to unequal application of heat to a generator, which are unavoidable in all plants, due to irregular composition of fuel and unavoidable variations in firing, or where generators are heated by such variable fuels as blast furnace gases, exhaust from industrial furnaces, or electric current, and to relieve a plant of variations in steam consumption of consumers connected ahead of an accumulator.

By maintaining constant boiler pressure, the arrangements of my invention give rise to a new system of operation of steam plants wherein regulation of heat supply to the boilers is effected in accordance with the state of charge of the accumulator. This method facilitates accumulation in a plant since it allows a smaller accumulator than otherwise would be necessary.

The apparatus, which, I believe, best characterizes my invention is the combination of a boiler, an accumulator, a passage for steam from the boiler to the accumulator, and automatically operating pressure con-

trolled means operating to simultaneously control said passage and maintain a constant or practically constant pressure in the boiler.

In one phase, my invention consists in the combination with one or more steam boilers, a steam conduit system connected therewith, an accumulator in the system serving to store steam when boilers generate more steam than is converted to use, and one or more consumers in the system, of one or more automatically operating valves regulating the flow of steam within the system and to the accumulator, said valve or valves being constructed and arranged to maintain a practically constant pressure in the boilers and various other parts of the system and to allow the process of steam generation to be unaffected by the accumulating action.

In another phase of my invention, it consists in a boiler unit, a consumer supplied therefrom at boiler pressure, an accumulator receiving steam from the boiler and connected to supply a consumer, and automatically operating pressure controlled means regulating the flow of steam from the boiler to or towards the accumulator and operating to maintain a constant pressure of steam both for the boiler and for the consumer regardless of the fact that the boiler generation or the consumption of the consumer or both may be at a varying rate and that therefore the said flow of steam may be at varying rate.

The invention consists also in the improved method involved in carrying my invention into effect.

In the particular forms of the invention shown by way of example, the automatically operating pressure controlled means is in the form of a valve mechanism which I term an "Over-flow valve", and it is inserted in a conduit leading steam in direction toward the accumulator, the said valve being so constructed that it will increase the steam flow upon an increase of the actuating pressure above a predetermined value, and will decrease the steam flow upon a decrease of the pressure below a predetermined value, thereby operating to maintain the actuating pressure constant.

The invention will be described more in detail with reference to the examples shown in the accompanying drawings, in which:

Fig. 1 is a diagrammatic view of a steam plant having my invention embodied therein in one form.

Fig. 2 is a similar view of a steam plant embodying my invention in modified form.

Fig. 3 is a similar view of still another modification of the invention.

Fig. 4 is a vertical sectional elevation of one form of over-flow valve.

Fig. 5 is a similar view of an over-flow valve and a reducing valve mechanically interconnected with each other.

Fig. 6 is a similar view of two reducing

valves mechanically inter-connected with each other.

Fig. 7 is a diagrammatic view of a steam plant equipped with over-flow valves, and with reducing valves of the forms shown in Figs. 4, 5 and 6.

Referring to the drawings:

In the steam plant diagrammatically shown in Fig. 1, steam is supplied by a steam generator P comprising one or more boilers through a conduit L_1 to a steam consumer D_1 . From the conduit L_1 , a conduit a leads to a steam accumulator A. In the conduit a an over-flow valve G_{1a} is arranged, which valve is constructed, as will be described more in detail later on, to permit the passage of steam when the pressure in front of the valve reaches a predetermined value and, when the pressure is within an operating range above this value, to increase the steam flow through the conduit on rise of the actuating pressure and decrease the steam flow on decrease of the actuating pressure, such actions of the valve being, in the normal operation of the plant, independent of the pressure in the accumulator. To the steam space of the accumulator A, which is partly filled with water, a conduit b is connected, in which a reducing valve R_{12} is inserted. This reducing valve controls the amount of steam supplied by the accumulator to the conduit L_2 to which the conduit b is connected, and the valve R_{12} is of a well known construction which will maintain a practically constant pressure in the said conduit L_2 from

which a steam consumer D_2 is fed. Another reducing valve R_{1a} which may be of similar construction to that of valve R_{12} is inserted in the conduit system in parallel with the said over-flow valve G_{1a} , and allows steam to flow into the accumulator A only in case the latter becomes completely discharged, as will be hereinafter more fully described.

A pressure gage M is mounted in the vicinity of the steam generator P and is connected by a pressure transmitting tube to the steam space of accumulator A. This gage indicates the pressure in the accumulator and, as the accumulator pressure is a function of the state of charge of the accumulator, the pressure gage is a means for indicating the state of charge.

The operation of the plant above described is as follows:

The steam generated in the generator P is led through the conduit L_1 partly to the steam consumer D_1 , and partly through the over-flow valve G_{1a} , to the accumulator A, and from the accumulator the steam passes to the steam consumer D_2 . Assuming that the steam pressure in the conduit L_1 is increased, due to decreased steam consumption of the consumer D_1 , or to increased steam generation, the over-flow valve G_{1a} will open more and will permit more steam to pass

into the accumulator A. Assuming on the contrary that the said steam pressure decreases, due to increased steam consumption, or to decreased steam generation, then the 5 over-flow valve will decrease the steam flow to the accumulator so as to maintain a practically constant pressure in the conduit L_1 .

Since the over-flow valve G_{1a} operates to maintain a constant pressure in the boilers 10 P and connected piping, the ordinary system of boiler plant operation wherein the intensity of heat supply to boilers is controlled in accordance with the pressure in the boilers is not adaptable to regulation of 15 the intensity of heat supply in systems according to the present invention. However, by means of the pressure gage M the intensity of heat supply can readily be regulated, the supply of heat to the boilers being 20 increased when the state of charge of the accumulator, as indicated by pressure gage M, is low, and decreased when the state of charge is high, so that reducing valve R_{1a} need not open and, on increase of pressure 25 in conduit L_1 , blowing of safety valves need not take place.

It has been found in practice that the fire-room force learns to regulate the fires just as easily by watching the pressure gage indicating the variable accumulator pressure 30 as by watching a gage indicating boiler pressure and the fires may be driven at a uniform intensity for the greater part of the time and need not be regulated as often as is the case without an accumulator, a matter which 35 has been proved by experiments to give higher combustion efficiency.

Should the accumulator become completely discharged, as might occur in exceptional 40 cases, additional steam must be taken from the generator independently of the control of the steam by the over-flow valve G_{1a} . This object is accomplished by the reduction valve R_{1a} , the construction of which is 45 such that it will open and allow steam to pass through it when the pressure in the accumulator, due to the discharge of the same, decreases beyond a certain value. In these circumstances, the pressure in the conduit L_1 will fall below the pressure required 50 to open the over-flow valve, and this valve will therefore remain closed and the whole quantity of steam will flow through the reducing valve to the accumulator and thence 55 to the consumer. In this way the consumer will be supplied with the necessary quantity 60 of steam independently of the control of the steam by the over-flow valve. To increase the generation of steam under these 65 conditions, in order to reestablish the normal working conditions of the plant, greater heat must be applied to the generator, the attendant being apprised of the necessity of doing so by observing the pressure indicator 70 M which is connected with the accumulator.

Fig. 2 shows the same arrangement of the over-flow valve in a steam plant in which the steam accumulator is connected in parallel with a conduit connecting the over-flow valve with the consumer, non-return valves V_1 and V_2 being inserted in the connections between the accumulator and said conduit. 75

Fig. 3 shows a plant comprising a main conduit L_1 connected to the generator, and several secondary steam conduit L_2 , L_3 and L_4 , carrying each a different steam pressure, and to which conduits the steam consumers D_1 , D_2 , D_3 and D_4 are connected. Between these conduits, the over-flow valves G_{12} , G_{23} and G_{3a} and the reducing valves R_{12} , R_{23} and R_{3a} are arranged as shown, and in the conduit L_4 the reducing valve R_{4a} is inserted. Supposing now for instance, that the pressure in the conduit L_2 increases above a predetermined value, the over-flow valve G_{23} will open and admit the surplus of steam into the conduit L_3 . From this conduit a certain amount of steam not being consumed by consumer D_3 , will pass through the over-flow valve G_{3a} in direction towards the accumulator A. The accumulator will be charged if the said quantity of steam passing through the over-flow valve G_{3a} exceeds the amount of steam required at the same moment by the steam consumer D_3 and, on the contrary, the accumulator will discharge in case the steam flow through the reducing valve R_{3a} exceeds the steam flow through the over-flow valve G_{3a} . 90 95 100

Be it supposed as another example, that the pressure in the conduit L_2 decreases below a predetermined value. Then the over-flow valve G_{23} will decrease the steam flow to the conduit L_3 . In exceptional cases it may happen, that this valve G_{23} will close completely. Then, with further decreasing pressure in the conduit L_2 , the reducing valve R_{12} will open and admit steam from the conduit L_1 into the conduit L_2 . Due to the cut-off of the steam supply through the over-flow valve G_{23} , the pressure in the conduit L_2 will also decrease and open the reducing valve R_{23} so as to admit steam from the conduit L_3 to the conduit L_2 . Before the reducing valve R_{23} begins to open, the over-flow valve G_{3a} will be closed so that no steam is supplied to the accumulator. In such a case, therefore, the consumer D_3 is fed with steam from the accumulator only. The reducing valve R_{3a} controls this steam flow from the accumulator to the consumer D_3 so as to maintain a practically constant pressure in the conduit L_4 . Should it happen, that the accumulator be completely discharged and fails to supply a sufficient quantity of steam to the conduit L_4 , in spite of the reducing valve R_{3a} being completely open, then, upon decrease of the pressure in the conduit L_4 below a predetermined value, 110 115 120 125 130

the reducing valve R_{3a} will be opened so as to admit the desired quantity of steam to the conduit L_4 .

From the above, it will be evident, that with such an arrangement of regulating means together with an accumulator, the latter will take care of all variations whenever they occur in the plant, and that the pressures in the conduits L_1 , L_2 , L_3 and L_4 will be maintained at respectively different, and practically constant values.

In Fig. 4 the detailed construction of an over-flow valve of one form suitable for carrying my invention into effect is shown.

In this figure it will be seen that the valve comprises a casing H provided at opposite sides with ports I and K , the port I being connected with the conduit L_1 of Fig. 1 and the port K being connected with the conduit a of Fig. 1. Within the casing is a chamber L connecting with the port K , which chamber is formed with aligned ports l and l_1 which are controlled by a cut-off valve member G comprising a plurality of discs carried by an operating stem N . This stem is connected with means for operating the valve member, which means consists of a bellows B_1 , the interior of which is in communication with the interior of the casing, and a spring F which bears against the bellows and exerts its force in opposition to the expansive action of the bellows. From this construction it will be understood that the spring F being set to resist a predetermined pressure, the bellows will expand and will move the valve member and begin to open the ports l and l_1 , when the pressure of the steam entering the casing through conduit L_1 overcomes the resistance of the spring, so that steam will flow through the valve and enter the conduit a and thence pass into the accumulator, it being understood that the increase of pressure above that necessary to start the opening movement will act to open the valve to a greater extent, until at a still greater predetermined pressure, the valve will be fully opened. It will thus be understood that if any predetermined value is selected, lying within the operating range between the predetermined value for complete closure of the valve and the predetermined value for full opening of the valve, that an increase of the actuating pressure above said any predetermined value will result in an increase of steam flow through the valve and a decrease of pressure below said any predetermined value will result in decrease of flow of steam through the valve. The over-flow valve is a "regulating" valve in normal operation.

The valve member G is balanced as shown, in respect to the action of the steam pressure thereon, so that the opening and throttling movements of the valve member under the influence of the pressures in the conduit in

front of the valve acting on the bellows are independent of the pressures acting on the valve member itself. In these circumstances the movements of the valve member under the influence of the pressure acting in front of the valve are independent of the pressure, the accumulator pressure in Figs. 1 and 2, acting behind the valve.

From the description of Fig. 3 it will be understood that with decreasing pressure, for instance in the conduit L_3 , the over-flow valve G_{3a} will close, and when completely closed and with further decreasing pressure, the reducing valve R_{23} will open. These two valves should therefore be so relatively adjusted, that with a certain pressure value in the conduit L_3 both valves will be closed; and should the pressure rise above said value, then the over-flow valve will open, and the reducing valve will remain closed; and should on the other hand, the pressure decrease below said value, the reducing valve will open and the over-flow valve will remain closed.

These relative actions of the two valves may be obtained by mechanically inter-connecting them, as shown for instance in Figs. 5 and 7. The reducing valve member 20 and the over-flow valve member 21 in Fig. 5 correspond to the respective valves R_{23} and G_{3a} of Fig. 3. From the drawing it will be seen that both valves are arranged in a common casing H_a , having near one end a port connected with the conduit L_2 of Figs. 3 and 7, and having near its opposite end a port connected to conduit L_3 of said figures. A third port is provided in the casing which is connected to the conduit L_a leading to the accumulator as shown in Fig. 7. A chamber L_{ax} extends into the casing from the port communicating with the conduit L_2 , which chamber is provided with aligned ports l_2 and l_3 ; and a second chamber L_{bx} extends into the casing from the port leading to the accumulator, which chamber is provided with aligned ports l_4 and l_5 . The two valve members 20 and 21, similar to the member G of Fig. 4, are provided to control the ports in the respective chambers, and these members slide on a stem S guided in the casing. A spring f of relatively small force encircles the stem between the two valve members and tends to hold them yieldingly in positions to close their respective ports. The stem is connected, in a manner similar to that shown in Fig. 4, to a bellows B_1 which is acted on by a spring F . The stem has fixed to it two collars R_0 and R_1 in position to engage the two valve members, the arrangement being such that when the stem is moved endwise in one direction, one of the collars will engage and open one of the valve members while not disturbing the other, and when the stem is moved endwise

in the opposite direction, the other valve member will be opened without disturbing the first.

From this description it will be understood that in the operation of the inter-connected reducing valve and the over-flow valve, if the pressure in conduit L_3 rises above a predetermined value, corresponding to the force of springs F and f , the bellows 10 will be expanded and the valve stem will be moved upwardly in Fig. 5, whereby the lower valve member 21 will be opened and will admit steam from conduit L_3 to conduit L_4 leading to the accumulator. In this 15 action the upper valve member 20 will be held in closed position by the spring f . On the other hand, if the pressure in conduit L_3 falls below a predetermined value, spring F will contract the bellows and will move the 20 stem downwardly, thereby opening the upper valve member 20 and admitting steam from conduit L_2 into the valve casing and thence to conduit L_3 , in which action the lower valve member will be held closed by 25 the spring f .

From the description of Fig. 3 it will be further understood that the reducing valve R_{3a} will open only when the reducing valve R_{4a} is completely open, the reducing valve 30 R_{3a} being closed when the reducing valve R_{4a} is only partially opened. This function 35 may be obtained by mechanically inter-connecting the two reducing valves as shown for instance in Fig. 6. Here it will be seen that a reducing valve member 30 corresponding to the reducing valve R_{4a} in Fig. 3 is arranged in a main valve casing E while another reducing valve member 31, corresponding to the reducing 40 valve R_{3a} of Fig. 3 is arranged in a secondary valve casing forming an extension of the first. The main casing is provided with oppositely disposed ports connected respectively with conduit L_4 and conduit L_3 , the first mentioned conduit being 45 connected with a chamber H_b extending into the casing and provided with aligned ports opening into the interior of the casing. The ports of the chamber H_b are controlled 50 by the valve member 30 which is carried by a valve stem S_1 movably guided in the casing. At its lower end the stem is connected with a bellows B_2 subject to the pressure in the casing, which bellows is acted on by a 55 spring F_x . At its opposite end the stem is connected with an open ended cylindrical slide constituting the valve member 31 movable within a cylindrical shell U having 60 ports O communicating with a port in the secondary casing and connected with the conduit L_3 . The relation of the parts described is such that when the valve member 65 30 is partially open, the cylindrical slide will cover the ports O in the shell U , and only when the valve member 30 is fully open,

will the ports O begin to be uncovered and communication then established between the conduits L_3 and L_4 .

Fig. 7 shows a plant of the same general arrangement as that shown in Fig. 3. In Fig. 7 however the plant is shown as being equipped with the different forms of valve constructions shown specifically in Figs. 4, 5 and 6; G_{12} designating the over-flow valve of the form of Fig. 4; $G_{23}+R_{12}$ and $G_{3a}+R_{23}$ designating the inter-connected over-flow and reducing valve constructions of Fig. 5; and $R_{3a}+R_{4a}$ designating the inter-connected reducing valves as shown in Fig. 6.

From the foregoing description of my invention, it will be understood that in the practice of the same, the supply of surplus steam to the accumulator arising either from increased steam generation or decreased steam consumption, is automatically regulated in accordance with the variations of pressure in the plant, and independently of the accumulator pressure; and it is manifest that while the mechanisms illustrated and described herein are suitable for carrying my improved method of steam supply into effect, the said method is not dependent for its practice on such apparatus and may be carried out by the use of apparatus of other forms.

By my invention as described above, many valuable advantages are secured, the most important of which will be briefly mentioned.

As all variations in steam generation and steam consumption are taken care of by the accumulator, modern steam generators with very small water space and with high efficiency may be employed. Further, owing to the constant generator pressure which is obtained, and the fact that forced firing of the generator is avoided, the generators will have longer life, and will not be subjected to injurious strains which would tend to cause deterioration. As the steam generation need only be such as to correspond to the average consumption of steam, generators of minimum size may be employed, thereby securing a maximum of economy in the operation of the plant.

Further, owing to the capability of the accumulator to deliver a large quantity of steam in a very short time, the capacity of the plant in the production of goods will be increased; and as the steam pressures in all of the conduits leading to the steam consumers are maintained at constant values, a more uniform and superior quality of goods may be secured.

It appears from the above description that the accumulator may be made so large that it will permit the boiler to generate continuously the average consumption at all times in which case no regulation of fires

would appear to be necessary except for unusual occurrences. However, in most plants, it is preferable to operate along a curve of varying average consumptions, that is, a curve of slowly varying steam generation or one having a given value for some time and then changing slowly to another given value for another period since, by this means, a smaller accumulator is possible and the complete advantages of the accumulator are nevertheless obtained. In the second case my new method of heat control is of the greatest importance.

I prefer to use this method in all accumulator installations and find that the use of the means for gaging the state of charge of the accumulator and the regulation of boilers thereby is actually indispensable in all plants including accumulators as herein described.

Having thus described my invention, what I claim is:

1. A boiler, an accumulator, a passage for steam from said boiler to said accumulator, and an automatic valve operating to simultaneously maintain a constant pressure in said boiler and control flow of steam through said passage.

2. A source of steam, a consumer supplied therefrom, an accumulator, a consumer supplied therefrom, a passage for steam from said source to said accumulator and an over-flow valve controlling said passage.

3. A steam plant comprising, in combination, a steam generator, a steam conduit system connected therewith, a steam accumulator connected in said system, means in said system to consume steam, a passage for steam in said system from said generator to said accumulator, and automatically operating movable means controlling said passage independently of the pressure in the accumulator.

4. The method of operating a steam plant which comprises generating steam at a different rate than the rate of consumption, conducting the surplus of generated steam over the momentary consumption to an accumulator and accumulating the same for use when the consumption exceeds the generation, controlling flow of steam to the accumulator and in the system so that the generator pressure is maintained constant while variations are permitted in the accumulator, indicating the state of charge of the accumulator and controlling the supply of heat to the generator in accordance with the state of charge of the accumulator.

5. A steam plant comprising, in combination, a steam boiler, a steam conduit system connected therewith, a steam accumulator connected in said system, means in said system to consume steam, a passage for steam in said system from said boiler to said accumulator, automatic means controlling said

passage independently of accumulator pressure and operating to maintain constant boiler pressure and means to indicate the state of charge of the accumulator and arranged to permit regulation of heat to the boiler in accordance with said state of charge.

6. A steam plant comprising, in combination, a steam boiler, a steam conduit system connected therewith, a steam accumulator connected in said system, means in said system to consume steam, a passage for steam in said system from said boiler to said accumulator, automatic means controlling said passage independently of accumulator pressure and operating to maintain constant boiler pressure, and a pressure gage mounted in the vicinity of said boiler and connected with the accumulator to indicate the pressure in the accumulator so that the supply of fuel to the boiler can be regulated in accordance with the state of charge of the accumulator.

7. A steam plant comprising, in combination, a steam boiler unit, a steam conduit system connected therewith, means in said system to consume steam, a steam accumulator in said system having a water space and a steam space and serving to regenerate steam, a passage for steam from said boiler unit to the water space of said accumulator, automatically operating movable means in said system controlling said passage independently of accumulator pressure and so that the boiler pressure is maintained constant, said accumulator being of sufficient capacity so that the boiler unit is made independent of steam demand and the arrangement being such that pressure variations are confined to the accumulator.

8. A source of steam, a consumer supplied therefrom at the pressure of the source, an accumulator having a steam space and a water space and serving to regenerate steam, a consumer supplied with steam from the accumulator, said accumulator being adapted to vary in pressure between the pressure of the second consumer and the source, a passage for steam from the source to the water space of the accumulator and an over-flow valve controlling said passage in response to pressure in the source and operating to maintain a constant pressure in the source and to maintain a constant pressure of steam for the first mentioned consumer.

9. In a steam plant, the combination with a steam generator, a steam conduit system connected therewith, a steam accumulator connected in said system, and a steam consumer supplied by the said accumulator, of a valve member inserted in a conduit leading steam in direction toward the accumulator, and means responsive to the generator pressure to operate the said valve member to increase the steam flow through the said con-

duit upon an increase of the said pressure above a predetermined value, while decreasing the steam flow upon a decrease of the said pressure below a predetermined value.

- 5 10. In a steam plant, the combination with a steam generator, a steam conduit system connected therewith, a steam accumulator connected in said system, said conduit system comprising a series of conduits, each 10 carrying a lower pressure than the pressure in the preceding conduit, a second series of conduits connecting the conduits of said first mentioned series of conduits, said second series of conduits leading steam in direction 15 toward said accumulator, a plurality of over-flow valve members inserted between conduits of said first mentioned series of conduits, one in each of the conduits of the said second series of conduits, means responsive 20 to the respective pressures in said connecting conduits in front of said valve members to operate each of said over-flow valve members to increase the steam flow through its conduit upon an increase of said pressure 25 above a predetermined value, while decreasing the steam flow upon a decrease of said pressure below a predetermined value, and steam consumers supplied from the conduits of the first mentioned series of conduits.
- 30 11. In a steam plant, the combination of a steam generator, a steam conduit system connected therewith, said conduit system comprising a plurality of conduits containing steam of different pressures, an accumulator 35 connected to one of said conduits, a connecting conduit between one of the said conduits and another conduit of different pressure, said connecting conduit leading steam in direction toward said accumulator, an over- 40 flow valve member in said connecting conduit, means responsive to the pressure in said connecting conduit in front of said valve member to operate the said valve member to increase the steam flow through the connect- 45 ing conduit upon an increase of said pressure above a predetermined value, while de- creasing the steam flow upon a decrease of the said pressure below a predetermined value and steam consumers connected to the 50 conduits of different pressures.

12. In a steam plant including a steam generator, a steam conduit system connected therewith, an accumulator in said steam conduit system and a plurality of consumers 55 connected in said system, the combination with a high pressure conduit of the said system and a low pressure conduit of the said system, of means responsive to the pressure in said high pressure conduit to pass steam 60 to said low pressure conduit upon an increase of pressure in said high pressure conduit above a predetermined value and means re- 65 sponsive to the pressure in said low pressure conduit to pass steam from said high pressure conduit to said low pressure conduit

upon a decrease of pressure in said low pressure conduit below a predetermined value.

13. A steam plant as specified in claim 11 provided with second means operated by the 70 pressure behind the said over-flow valve member and adapted to admit steam in direction toward said accumulator upon a de- crease of the last said pressure below a pre- determined value. 75

14. In a steam plant, the combination with a steam generator, a steam conduit system connected therewith, a steam accumulator connected in said system, a consumer supplied by the said accumulator, a conduit 80 leading steam in direction toward said accumulator, an over-flow valve member inserted in said conduit, means responsive to the pres- 85 sure in said conduit in front of said valve member to operate the same to increase the steam flow through the conduit upon an in- crease of said pressure above a predeter- 90 mined value while decreasing the steam flow upon a decrease of the said pres- 95 sure below a predetermined value and a reducing valve member arranged in par- 100 allel with the said over-flow valve mem- ber, and means responsive to the pressure in the conduit behind said over-flow valve mem- 105 ber to open the said reducing valve member upon a decrease of pressure in the conduit behind said over-flow valve member below a predetermined value.

15. A steam plant comprising, in combi- 110 nation, a steam generator, a steam conduit 115 system connected therewith, a low pressure conduit in said system, an accumulator connected to said low pressure conduit, a con- 120 sumer connected to said low pressure con- 125 duct, a conduit of higher pressure in said system, a consumer connected to said con- 130 duct of higher pressure, means responsive to the pressure in said conduit of higher pres- 135 sure to pass steam from said conduit of higher pressure to said low pressure con- 140 duct when said pressure is above a pre- 145 determined value and means responsive to pressure in said low pressure conduit to pass steam from said conduit of higher pres- 150 sure to said low pressure conduit when said accumulator is discharged.

16. A steam plant as specified in claim 10, in combination therewith, a reducing valve member arranged in parallel with each over- 155 flow valve member and means provided for each reducing valve member, responsive to the pressure in the conduit behind said re- 160 ducing valve member to open the same upon a decrease of the last said pressure below a predeter- 165 mined value. 170

17. In a steam plant, the combination with a steam generator, a steam conduit system connected therewith, a steam accumulator connected in said system, of a conduit lead- 175 ing steam toward said accumulator, an over-

flow valve member inserted in said conduit, means responsive to the pressure in said conduit in front of said valve member to operate the same to increase the steam flow 5 through the said conduit upon an increase of the said pressure above a predetermined value while decreasing the steam flow upon a decrease of the said pressure below a predetermined value, a conduit leading steam 10 from said accumulator, a consumer connected to said last-mentioned conduit, a reducing valve member inserted in this last-mentioned conduit, means responsive to the pressure in the said last-mentioned conduit 15 beyond the reducing valve member to open said reducing valve member upon a decrease of the last said pressure below a predetermined value while decreasing the steam flow upon an increase of the last said pressure 20 above a predetermined value.

18. In a steam plant, the combination with a steam generator, a steam conduit system connected therewith, a steam accumulator connected in said system, of a 25 conduit leading steam toward said accumulator, an over-flow valve member inserted in said conduit, means responsive to the pressure in said conduit in front of said valve member to operate the same to increase the 30 steam flow through the said conduit upon an increase of the said pressure above a predetermined value while decreasing the steam flow upon a decrease of the said pressure below a predetermined value, a conduit 35 leading steam from said accumulator, a consumer connected to said last-mentioned conduit, a reducing valve member inserted in this last-mentioned conduit, means responsive to the pressure in said last-mentioned 40 conduit beyond the reducing valve member to open said reducing valve member upon a decrease of the last said pressure below a predetermined value while decreasing the steam flow upon an increase of the last said 45 pressure above a predetermined value, and a second steam consumer supplied from the conduit in front of the over-flow valve member.

19. In a steam plant, the combination with a steam generator, a steam conduit system connected therewith and a steam accumulator connected in said system, of a conduit leading steam toward said accumulator, said conduit being supplied with steam from 55 said generator, a consumer supplied by said accumulator, a valve mechanism inserted in said conduit responsive to the pressure in said conduit in front of the same and operating to maintain the said pressure constant, a second conduit to supply steam to the first mentioned conduit, and a reducing valve mechanism in the second conduit interconnected with the first mentioned mechanism. 60

20. In a steam plant, the combination 65

with a steam generator, a steam conduit system connected therewith, a steam accumulator connected in said system, of a conduit leading steam toward said accumulator, a valve member inserted in said conduit, 70 means responsive to the pressure in said conduit in front of said valve member to operate the same to maintain said pressure constant, a conduit leading steam from said accumulator, a consumer connected to said last-mentioned conduit, a reducing valve member inserted in this last-mentioned conduit, means responsive to the pressure in said last-mentioned conduit beyond the reducing valve member to open said reducing 75 valve member upon a decrease of the last said pressure below a predetermined value while decreasing the steam flow upon an increase of the last said pressure above a predetermined value, a second reducing valve member connected in parallel with the first mentioned valve member, said second reducing valve member being interconnected with said first reducing valve member and means to open the second reducing valve member 80 only when said first reducing valve member is completely open.

21. In a steam plant, the combination with a steam generator, a steam conduit system connected therewith, a steam accumulator connected in said system, of a conduit leading steam toward said accumulator, an over-flow valve member inserted in said conduit, means responsive to the pressure in said conduit in front of said valve member 95 to operate the same to increase the steam flow through the said conduit upon an increase of the said pressure above a predetermined value while decreasing the steam flow upon a decrease of the said pressure below a predetermined value, a conduit 100 leading steam from said accumulator, a consumer connected to said last-mentioned conduit, a reducing valve member inserted in this last-mentioned conduit, means responsive to the pressure in said last-mentioned conduit beyond the reducing valve member 105 to open said reducing valve member upon a decrease of the last said pressure below a predetermined value while decreasing the steam flow upon an increase of the last said pressure above a predetermined value, and a second steam consumer supplied from the conduit in front of the over-flow valve member. 110

22. In a steam plant, the combination of a steam generator, a steam consumer, a conduit connecting the generator with the con- 115

- sumer, an over-flow valve member inserted in the said conduit, means for operating the same to increase the steam flow through the conduit upon an increase of the pressure in the conduit in front of the over-flow valve member, while decreasing the steam flow upon a decrease of pressure, a steam conduit connected in parallel with the first mentioned conduit, a steam accumulator connected in the second mentioned conduit, and non-return valves in the last mentioned conduit.
23. A source of steam, means to consume steam, means to conduct steam from the source to the consuming means, an accumulator, means to conduct steam from the accumulator to the consuming means, a passage for steam from said source to said accumulator and an over-flow valve controlling said passage.
24. A steam plant comprising, in combination, a steam generator, a steam conduit system connected therewith, a steam accumulator connected in said system, a steam consumer with variable steam consumption supplied directly from the generator, a steam consumer supplied with steam from the accumulator, and automatically operated movable means adapted to control the passage of the surplus generated steam above the momentary consumption and pass this surplus steam to the accumulator independently of the pressure therein.
25. A steam plant comprising, in combination, a steam generator, an accumulator, a consumer, said accumulator and consumer being connected in parallel to said generator to receive steam therefrom, a steam consumer supplied with steam from the said accumulator, pressure actuated means adapted to control the flow of surplus steam to the accumulator, said means being inactive under a given value of the actuating pressure and adapted to become active and to be operated to control the steam flow to the accumulator when said pressure value is exceeded.
26. In a steam plant, the combination with a steam generator, a steam conduit system connected therewith, a steam accumulator connected in said system, and a steam consumer supplied by the said accumulator, of a balanced over-flow valve inserted in a conduit leading steam in direction toward the accumulator, and a steam consumer receiving steam in front of said valve.
27. In a steam plant, in combination, a boiler, an accumulator, a passage for steam from said boiler to said accumulator, a balanced valve in said passage comprising a reciprocating stem, a plurality of discs attached thereto, each controlling an opening in said valve, pressure operated means to move said stem, to increase the opening through the valve upon increase of pressure in front of the same, and a consumer supplied by the accumulator.
28. In a steam plant, the combination with a steam generator, a steam conduit system connected therewith, a steam accumulator connected in said system and a steam consumer supplied by the said accumulator, a conduit leading steam in direction toward said accumulator, a branch connection leading from said conduit, a second consumer connected to said branch connection, an over-flow valve member inserted in the said conduit beyond the said branch connection and means adapted to operate the said valve member to increase the steam flow through the said conduit upon an increase of the pressure in the said conduit in front of the said valve member above a predetermined value, while decreasing the steam flow upon a decrease of the said pressure below a predetermined value.
29. In a steam plant, the combination with a steam generator, a steam conduit system connected therewith, a steam accumulator connected in said system, and a steam consumer supplied by the said accumulator, of an over-flow valve inserted in a conduit leading steam toward the accumulator, said over-flow valve comprising means adapted to operate the valve to increase the steam supply through the said conduit upon an increase of the pressure in the said conduit in front of the valve above a predetermined value, while decreasing the steam flow upon a decrease of the said pressure below a predetermined value, and a steam consumer supplied from the said conduit in front of the said over-flow valve.
30. In combination, a waste heat boiler, a consumer, an accumulator, a passage for steam from the accumulator to the consumer, a passage for steam from the waste heat boiler to the accumulator and an over-flow valve controlling the last-named passage.
31. In combination, a boiler having a variable supply of fuel, a consumer, an accumulator, a passage for steam from the boiler to the accumulator, an over-flow valve controlling said passage and means to conduct steam from said accumulator to said consumer.
32. In combination, a waste heat boiler, a steam conduit system connected to receive steam therefrom, a steam accumulator connected in said conduit system, a consumer supplied by said accumulator, a valve member inserted in a conduit of said system leading steam in direction toward the accumulator, means adapted to operate said valve member to increase the steam flow through the same upon an increase of pressure above a predetermined value and decrease the steam flow upon a decrease of pressure below a predetermined value.

33. The method of producing and dispensing steam which comprises producing steam at a different rate than the rate of consumption, accumulating steam when the consumption is less than the steam generation, regulating the amount of steam accumulated so that the pressure of the generated steam is maintained constant, and withdrawing steam to use from the accumulator when the consumption exceeds the momentary steam generation.

34. That improvement in the art of controlling steam plants employing steam accumulators which consists in automatically regulating the steam flow to the accumulator in accordance with the generator pressure,

and independently of the accumulator pressure so that the generator pressure is maintained constant.

35. That improvement in the art of generating and dispensing steam in a steam plant equipped with a steam generator, steam consumers, and a steam accumulator which consists in automatically regulating the flow of steam to and from the accumulator, so as to maintain a constant steam pressure in the generator and for the consumers and confining variations of pressure in the plant to the accumulator.

In testimony whereof I affix my signature.

JOHANNES KARL RUTHS.
